UNITED STATES PATENT OFFICE.

FELIX RIVANOV, OF CHICAGO, ILLINOIS, ASSIGNOR TO THE ANDERSON COMPANY, OF GARY, INDIANA, A CORPORATION OF INDIANA.

DESIGN FOR A RADIATOR-CAP ORNAMENT.

Application filed February 13, 1928. Serial No. 25,421. Term of patent 3½ years.

To all whom it may concern:

Be it known that I, FELIX RIVANOV, a citizen of the United States, residing at Chicago, in the county of Cook and State of Illinois, have invented a new, original, and ornamental Design for a Radiator-Cap Ornament (Case B), of which the following is a specification, reference being had to the accompanying drawing, forming a part thereof.

Figure 1 is a view in elevation showing one face of the device; and

Figure 2 is a side elevation of the same.

I claim:

The ornamental design for a radiator cap ornament as shown.

FELIX RIVANOV.
